CLAIM

We claim the ornamental design for an indoor growing unit, as shown and described.

DESCRIPTION

FIG. 1 is a front perspective view of an indoor growing unit.

FIG. 2 is a side overhead perspective view thereof.

FIG. 3 is a rear perspective view thereof.

FIG. 4 is a rear perspective view thereof.

FIG. 5 is rear overhead perspective view thereof.

FIG. 6 is a bottom perspective view thereof.

FIG. 7 is a front perspective view thereof with inserts from the growing trays removed.

FIG. 8 is a front perspective view thereof with two of the growing trays removed and the insert removed.

FIG. 9 is a left side view thereof.

FIG. 10 is a right side view thereof.

FIG. 11 is a front elevational view thereof.

FIG. 12 is a rear elevational view thereof.

FIG. 13 is an exploded parts view showing the components thereof.

FIG. 14 is a front perspective view of a second embodiment of an indoor growing unit.

FIG. 15 is a side overhead perspective view thereof.

FIG. 16 is a rear perspective view thereof.

FIG. 17 is a rear perspective view thereof.

FIG. 18 is rear overhead perspective view thereof.

FIG. 19 is a bottom perspective view thereof.

FIG. 20 is a front perspective view thereof with inserts from the growing trays removed with a capillary mat in the bottom of the growing trays.

FIG. 21 is a front perspective view thereof with two of the growing trays removed and the insert removed with the capillary mat in the bottom of the growing tray.

FIG. 22 is a left side view thereof.

FIG. 23 is a right side view thereof.

FIG. 24 is a front elevational view thereof.

FIG. 25 is a rear elevational view thereof.

FIG. 26 is an exploded parts view showing the components thereof, including the capillary mats.

FIG. 27 is a front perspective view of a third embodiment of an indoor growing unit.

FIG. 28 is a side overhead perspective view thereof.

FIG. 29 is a rear perspective view thereof.

FIG. 30 is a rear perspective view thereof.

FIG. 31 is rear overhead perspective view thereof.

FIG. 32 is a bottom perspective view thereof.

FIG. 33 is a front perspective view thereof with inserts from the growing trays removed.

FIG. 34 is a front perspective view thereof with two of the growing trays removed and the insert removed .

FIG. 35 is a left side view thereof.

FIG. 36 is a right side view thereof.

FIG. 37 is a front elevational view thereof.

FIG. 38 is a rear elevational view thereof.

FIG. 39 is an exploded parts view showing the components thereof.

FIG. 40 is a front perspective view of a fourth embodiment of an indoor growing unit.

FIG. 41 is a side overhead perspective view thereof.

FIG. 42 is a rear perspective view thereof.

FIG. 43 is a rear perspective view thereof.

FIG. 44 is rear overhead perspective view thereof.

FIG. 45 is a bottom perspective view thereof.

FIG. 46 is a front perspective view thereof with inserts from the growing trays removed with a capillary mat in the bottom of the growing trays.

FIG. 47 is a front perspective view thereof with two of the growing trays removed and the insert removed with the capillary mat in the bottom of the growing tray.

FIG. 48 is a left side view thereof.

FIG. 49 is a right side view thereof.

FIG. 50 is a front elevational view thereof.

FIG. 51 is a rear elevational view thereof; and,

FIG. 52 is an exploded parts view showing the components thereof, including the capillary mats.

The broken lines in the drawings illustrate environmental structure on the article and form no part of the claimed design.
